UNITED STATES PATENT OFFICE.

FRANK WALLACE, OF YOUNGSTOWN, OHIO, ASSIGNOR TO ANTHONY SCHIELE, OF YOUNGSTOWN, OHIO.

AUTOMOBILE JACK.

Application filed September 28, 1923. Serial No. 665,400.

To all whom it may concern:

Be it known that FRANK WALLACE, a citizen of the United States of America, residing at 20 W. Front St., Youngstown, in the 5 county of Mahoning and State of Ohio, has invented certain new and useful Improvements in Automobile Jacks, of which the following is a specification.

This invention relates to improvements in 10 automobile jacks and has for its principal object to provide a simply constructed device having a pivotally mounted bearing block upon which an axle or other suitable part of machine rests when the device is in 15 operation. A further object of the invention is to provide an inverted U-shaped member carrying the above mentioned pivotally mounted block, said U-shaped member pivotally secured between the upper ends 20 of a bifurcated lever.

A still further object of the invention is to provide a device which can be very inexpensively manufactured, of very few parts, and yet be very strong and efficient.

25 With the above and many other objects in view, the invention resides in the novel features of construction, and the combined arrangement of parts which will hereinafter be more particularly described and claimed 30 and shown in the drawings herein:

Figure 1 represents a front elevation of the device.

Figure 2 represents a vertical edge view of the device.

35 Figure 3 represents a vertical edge view of the device in a position for lifting.

Figure 4 is a detailed view showing a collapsible handle or lever extension.

In its preferred embodiment, my invention 40 comprises a support 1 carrying 2 parallel supporting standards 2, to which there is secured a lever 3 fulcrumed at points 4 by means of a fulcrum bolt 5. It will be seen that this lever 3 is bifurcated at its 45 upper end and carries an inverted U-shaped member 6 between the ends 7 of the lever 3. This inverted U-shaped member is pivotally secured to said ends 7 by means of a bolt 8. Centrally located upon the upper surface 9 50 of the inverted U-shaped member 6 there is provided a pivotally mounted bearing block 10. The lower end 11 of the lever 3 is collapsible and folds up by means of a hinge 12. It will not be found necessary to use 55 this lower end 11 except when an extremely

heavy weight is to be lifted then in order to start the load upwardly this lower end 11 may be turned outwardly upon the hinge 12 thereby increasing the leverage. Another function of the lower end 11 is to act as a 60 stop before the lever 3 reaches an upright position. It will be noticed that I have a sharp lug 13 positioned at the extreme end 14 of the lower end 11 of the lever 3. When it is decided to lift the weight slightly this 65 sharp lug 13 may be used to come in contact with a floor or ground thereby holding the weight suspended upon the pivotally mounted bearing block 10 without giving a full upward lift by bringing the lever 3 past a dead 70 center when the same comes in contact with a stop 15 and the inverted U-shaped member is brought up against a stop 16. It is, of course, obvious that usually the operator 75 will push the lever 3 down until the dead center is past and comes to rest against the stops 15 and 16 as shown in Figures 1 and 2.

From the foregoing description it will be seen that I have invented an extremely simple device by which the wheel of the automobile or other object, may be readily lifted. It is obvious that this simply constructed jack can be very readily operated merely by one down stroke of the lever 3, and that the device may be positioned underneath the 80 weight to be lifted so that the lever may take varying positions due to the pivotally mounted bearing block 10. Many machines have a brace rod underneath the axle, and in order to provide a bearing block that will 85 be suitable to different types of machines I have therefore provided a recess 17 centrally located upon the top of the pivotally mounted bearing block 10.

What I claim is:

1. In a device of the class described a support member, two parallel support standards, bifurcated lever fulcrumed at the upper ends of said parallel supporting standards, an inverted U-shaped member pivotally secured to the upper end of said bifurcated lever, a bearing block pivotally secured upon the upper portion of said inverted U-shaped member, a collapsible lower end to said lever, means for holding parts 100 in a located position, substantially as described for the purpose set forth.

2. In the device of a class described a support member two upright parallel support members, a pivotally secured lever posi- 105

tioned within said parallel supporting members, an inverted U-shaped member pivotally secured within the upper ends of said lever, a pivotally secured bearing block positioned upon said inverted U-shaped member, a collapsible lower end of said lever, a sharp lug formed at the extreme end of said collapsible part of said lever, means for holding said lever and connecting parts in a fixed

position when the weight has been elevated to its highest point, substantially as described for the purpose set forth.

In testimony whereof I affix my signature.

FRANK WALLACE.

Witnesses:

ANTHONY SCHIELE,
HARRIET SWANSON.
